(57) **CLAIM**

We claim the ornamental design for a flagpole having a display surface, as shown and described.

DESCRIPTION

FIG. 1 is a front, left, top perspective view of the flagpole having a display surface;

FIG. 2 left side view thereof;

FIG. 3 is a front view thereof;

FIG. 4 is a rear view thereof.

FIG. 5 is a top view thereof; and,

FIG. 6 is a bottom view thereof.

The right side view of the flagpole having a display surface is a mirror image of FIG. 2.
